ARTHUR N. KERR, OF BELLEVUE, PENNSYLVANIA, ASSIGNOR TO ROCKGAS PRODUCTS COMPANY, OF CORAOPOLIS, PENNSYLVANIA, A CORPORATION OF DELAWARE.

APPARATUS FOR PRODUCING ARTIFICIAL GAS.

Application filed June 4, 1924. Serial No. 717,779.

This invention relates to an apparatus for utilizing a cut containing the extremely light volatile constituents obtained from natural gas gasoline in the manufacture of a 5 commercially practical artificial gas possessing substantially uniform heating qualities.

It is well known that natural gas gasoline, that is gasoline recovered from natural gas by either the compression and cooling process or various absorption processes, contains 10 large percentages of combustible constituents of gas which are lighter than the gasoline constituents, being chiefly ethane, propane, and butane, each of which is a gas 15 under normal atmospheric temperature and pressure conditions.

It is also well known that gasoline containing such lighter constituents is rendered 20 unsuitable for many purposes, such for instance as motor fuel, that these lighter constituents have frequently been partially removed so as to leave a gasoline better suited for use as a motor fuel, that some attempts have been made along the same lines by distillation in an effort to rid the gasoline of 25 the generally considered objectionable and disadvantageous lighter volatile constituents referred to, and that heretofore a large portion of the cuts containing such lighter 30 constituents have been considered as of little value and commercially used to but a limited extent.

It is an object of this invention to eliminate the large waste of valuable natural 35 resources incident to previous practices, encouraging the production of more stable grades of natural gas gasoline suitable for motor fuels, and utilizing the generally considered undesirable cuts containing the 40 lighter volatile constituents in the manufacture of artificial gas of substantially uniform calorific value or heating quality.

Ordinarily, in order to be used as a motor fuel without prejudicial effects arising from 45 the presence of the lighter combustible constituents, natural gas gasoline must have an initial boiling point above about 60 degrees Fahrenheit under atmospheric pressure, and a vapor tension of less than about ten pounds per square inch at 100 degrees Fahrenheit, and when secured by distillation, the specific 50 gravity of distillation is preferably continued until the residue is not more than about 80 degrees Baumé. In the practice of the present invention the cuts produced 55

in the nature of by-products containing the lighter volatile constituents during the conversion of natural gas gasoline into more suitable form for motor fuel are utilized.

The cut of lighter volatile constituents, 60 suitably confined under pressure in a closed vessel, wholly or partially in liquid form or what might be termed semi-liquid form, is first subjected to aeration by passing streams of air or other desirable gaseous 65 carrier therethrough, which when intimately mixed therewith in suitable proportions will prevent condensation of the constituents, and the mixture thus produced then intermingled with an additional supply of the 70 gaseous carrier to form an artificial gas, while constantly governing the relative proportions of the mixture and carrier to maintain the calorific or heating value of the gas produced substantially uniform. 75

In the accompanying drawings constituting a part hereof and in which like reference numerals designate like parts, Fig. 1 is a plan view diagrammatically illustrating apparatus for practicing the invention; Fig. 2 is a view in elevation of connecting apparatus; and Fig. 2^a illustrates the remaining portion of the apparatus shown in Fig. 2. 80

In the drawings, 1 designates a continuously running gas engine which is operatively connected by means of the belt 2 to a compressor 3. The inlet to the compressor 3 is indicated at 4 while its discharge line is shown at 5 which communicates with the 90 pipe 6. A pressure actuated unloader or regulator valve 7 in the inlet conduit 4 is controlled in response to the discharge pressure in line 5 by means of the branch pipe 8. 85

The pipe 6 communicates with a conduit 9 forming the discharge line of a compressor 10 driven through means of the belt 11 from an electric motor 12. The operation of the motor 12 is controlled by means of a pressure actuated switch 13 responsive to the 95 pressure conditions in the discharge conduit 9 through the pipe 14. The conduit 9 communicates with the upper end of a service storage tank 15 which is adapted to receive its supply from either or both of the air compressors 3 and 10. 100

Leading from the opposite end of the pressure tank 15 to which conduit 9 is connected is a pipe 16 having interposed therein the check valve 17 for preventing back 110

flow towards the tank. At a point beyond the check valve 17 pipe 16 forms two branches 18 and 19. The branch 18 has interposed therein the pressure reducing valve 20, and communicates with a depending pipe 21 projecting downwardly to a point adjacent the bottom of an aerating or carbureting tank 22 where it communicates with a series of perforated pipes 23 for discharging 10 the gaseous carrier such as air delivered from the service tank into the body 24 of the cut containing the light volatile constituents, previously referred to.

The branch 19 has interposed therein the 15 pressure reducing valve 25 and delivers to a mixing device 26 from which the delivery main 27 for distributing the artificial gas leads, the main having interposed therein the tank 27' of sufficient size to care for 20 fluctuations in the quality of the gas during the heating or cooling of the thermostatic valve.

A second electric motor is indicated at 28 which drives an air compressor 29 through 25 the belt 30, and is governed by means of a pressure actuated switch 31 communicating with the discharge pipe 32 of the compressor through the pipe 33, in this manner rendering the operation of the motor 28 responsive to the pressure existing in the discharge line 32. The air discharge line 32 delivers to an emergency air storage tank 34 at one end thereof, while the stored fluid is conducted from the tank at its opposite 35 end through the pipe 35 communicating with the pipe 19 at the connection 36, and having interposed therein the pressure reducing valve 37.

A branch pipe 38, in which is interposed 40 the pressure reducing valve 39, leads from the pipe 35 and is connected with the depending pipe 21 at the connection 40, and, if desired, may also be connected with the pipes 23 by means of a depending branch 41.

The mixture produced by the passage of 45 the air carrier through the body 24 collects at the top of tank 22, and is conducted by the pipe 42 to the mixer 26. Preferably the pipe 42 discharges into a perforated nozzle 43 located within the body of the mixer 50 whereby to intimately intermingle with the air delivered through pipe 19.

Interposed in pipe 42 between the tank 55 22 and the mixer 26, is a thermostatically controlled valve 44, the thermostat for controlling the same being generally shown at 45. This thermostat may consist, as illustrated, of an outer expansible and contractible cylindrical shell 46 in which is centrally located a rod 47, which through the levers 48 and 49 is adapted to move the head of the valve 44 away from its seat upon shortening of the shell, the valve head being urged to its closed position by means of a 60 spring shown at 50. The thermostat is re-

sponsive to variations in the intensity of the flames of the burner 51 which is supplied through the pipe 52 with gas from the delivery main 27, a valve 53 being interposed in the pipe 52 so that the gas supplied to the 70 burner may be varied to adjust the calorific value of the gas produced, as desired, in a manner subsequently more fully described.

The compressor 3 is adapted to deliver any suitable gaseous fluid carrier, preferably 75 air, which will prevent condensation of the lighter volatile constituents of the cut used, into the pressure tank 15, the unloader or regulator valve 7 being set to deliver the air to the service tank at a pressure of substantially fifteen pounds per square inch. The compressor 10 is likewise adapted to deliver a gaseous carrier such as air to the service tank, but the pressure actuated switch 13 is set so that the motor 12 is maintained inactive as long as the desired predetermined pressure is maintained in the service tank by means of the compressor 3, but to start the motor in operation whenever the pressure in the service tank falls slightly below this point. For instance, when the valve 7 is set to deliver at fifteen pounds per square inch, the switch 13 is set to start the motor 12 when the pressure per square inch in the service storage tank falls to say 95 approximately twelve pounds per square inch.

The air compressor 29 delivers to the emergency storage tank 34 and has the controlling valve 31 for its motor 28 set to maintain a pressure in the tank 34 of approximately sixty to sixty-five pounds per square inch.

The pressure reducing valve 20 is adjusted to maintain a pressure of approximately nine 105 pounds per square inch at the delivery side thereof, while the pressure reducing valve 39 is set to permit flow therethrough from the emergency tank 34 whenever the compressed air at the delivery side of the 110 valve 20 and within the carbureting tank falls below the pressure at which it is normally maintained. For instance, should the supply of air from the service tank 15 fail for any reason so that the pressure at the delivery side of the valve 20 and within the carbureting tank falls to approximately eight pounds per square inch, then the valve 39 will be actuated so as to permit flow of air from the emergency storage tank 34 through the pipe 38 and the branch pipes 41 and 21 into the pipes 23 located at the bottom of the carbureting tank, thus furnishing the necessary supply of the air during such periods from the 115 emergency storage tank, and precluding interruption of the operation of the plant because of lack of supply in the service air tank 15.

The pressure reducing valve 25 is adjusted 120

to normally permit flow of the air through the pipes 16 and 19 from the service tank 15 to the mixer 26, and to maintain a pressure of approximately twelve pounds per square inch at the discharge side thereof. The pressure reducing valve 37 is adjusted to remain normally closed while a pressure of twelve pounds per square inch is maintained in the pipe 19 from the service tank 15 in the manner described, but to open and permit flow from the emergency storage tank 34 into the pipe 19 whenever the pressure therein drops to approximately eleven pounds per square inch. In this way whenever failure of sufficient air from the service tank 15 occurs, the pressure reducing valve 37 is brought into play to insure a supply of the air from the emergency storage tank to the mixer by way of the pipes 35 and 19.

The carburetting tank 22 is filled with the cut obtained from natural gas gasoline, as previously described, from time to time. The flow of the air either from the service tank 15 or from the emergency storage tank 34 causes the same to be discharged from the perforated pipes 23 and intimately intermingled with the constituents of the cut so as to form an extremely rich mixture which is delivered through the pipe 42 and nozzle 43 into the mixer 26 where it is in turn intimately intermingled with the additional quantity of air fed to the mixer through the pipe 19. The intermingling of the rich mixture previously formed with the air in the mixer 26 produces an artificial gas of desirable heating qualities which is carried to the points of use through the delivery main 27.

The flow of the rich mixture from the carburetting tank 22 through the pipe 42 to the mixer is controlled by means of the valve 44 in response to the calorific value of the gas delivered to the main 27 by means of the valve 44. The valve 44 is thermostatically controlled so as to open and permit an increased flow of the mixture to the mixer 26 whenever the calorific value of the gas ultimately produced falls below the predetermined point for which the apparatus is adjusted, and similarly is closed to reduce the flow through the pipe 42 when there is an increase in the calorific value of the gas in the main 27. This control is accomplished by means of the burner 51 and the thermostatic elements associated with the valve 44. The burner 51 is supplied with gas taken from the main 27, the flames of which play against the tubular member 46. Whenever the calorific value of the gas in the delivery main increases, the heating effect of the burner is correspondingly increased causing a lengthening of the element 46, permitting the spring 50 to force the valve head toward its seat to diminish the flow through

the pipe 42. Similarly, whenever a decrease in the calorific value of the gas in the main 47 occurs the intensity of the burner flames is correspondingly decreased, resulting in a shortening of the element 46. The core or 70 rod 47, due to the fact that it abuts the closed end of the tubular element 46, is consequently forced towards the valve body, and through the levers 48 and 49, the latter of which contacts the stem attached to the 75 valve head, forces the valve from its seat thereby increasing the flow of the rich gas through the pipe 42. In this manner, the quantities of the rich gas and the air delivered to the mixer 26 are properly proportioned to maintain the gas ultimately produced at a substantially uniform calorific value.

Applicant's method, as well as the apparatus for carrying out the invention, will be 85 readily understood from the above description. The operation of the system in general is as follows:—the fluid carrier, which is preferably air, is normally supplied to the service tank 15 by means of the compressor 3, and is maintained at a pressure of approximately fifteen pounds per square inch therein, the compressor 29 being brought into operation to maintain the desired supply of air in the tank 15 only upon 90 the failure of the compressor 3. The compressor 29 is actuated through its pressure controlled switch 31, at intervals whenever pressure in the tank 34 falls below about 65 pounds per square inch so as to maintain a reserve supply of the air in the emergency storage tank 34, the frequency of 95 operation of this compressor depending entirely upon the amount of air which must be withdrawn therefrom to maintain the 100 operation of the system.

Normally, the air flows from the service tank 15 both to the carburetting tank 22, and to the mixer 26 through pipe 19. Should, for any reason, the supply of the 110 carrier in the service tank 15 fail, or fall below a pressure sufficient to maintain a pressure of between eight and nine pounds per square inch within the carburetting tank, and a pressure of approximately eleven to 115 twelve pounds per square inch in the pipe 19 beyond the valve 25, a flow of the carrier from the emergency storage tank 34 through the valve 39 to the carburetting tank and through the valve 37 to the pipe 120 19, will be permitted, thus drawing upon the reserve supply of the air in the tank 34 to maintain the operation of the system.

The passage of the air through the carburetting tank 22 in the manner previously 125 set forth, produces a rich gas in an obvious fashion, which gas is subsequently intimately intermingled with an additional supply of the air to ultimately produce the gas delivered through the main 27 to the point of 130

use, the control of the flow of the rich gas from the carburetting tank to the mixer being controlled in response to the calorific value of the gas ultimately produced so as to properly proportion the rich gas and the additional air in the mixer to maintain the gas produced at a predetermined calorific value.

It is noted that the thermostatic control of the rich gas supplied to the mixer not only prevents the production of gas having a calorific value above a certain predetermined point, but should for any reason a failure of the air occur, the valve 44 will be closed to shut off the supply from the carburetting tank. It is also obvious that by properly adjusting the valve 53, the system may be regulated to deliver gas of any desired calorific value within the ranges for which the system is designed.

I claim:

1. An apparatus for producing carburetted air gas of substantially uniform calorific value comprising in combination a service air storage tank, a carburetting tank for producing carburetted gas, a gas mixer, conduits leading from the said service tank to the carburetting tank and mixer, respectively, a conduit connecting the carburetting tank and mixer, a valve interposed in the pipe from the carburetting tank to the mixer, and means for controlling the actuation of said valve in response to the calorific value of the gas produced in the mixer.

2. An apparatus for producing carburetted air gas of substantially uniform calorific value comprising in combination a service air storage tank, an emergency storage tank for air, a carburetting tank for producing a carburetted gas, a gas mixer, conduits leading from the said air tank to the carburetting tank and mixer, respectively, a pipe connecting the carburetting tank and mixer, a pressure reducing valve interposed in the conduit leading from the service air tank to the carburetting tank for delivering the air to the carburetting tank at a predetermined pressure, a conduit connecting the emergency storage tank with the carburetting tank, and a pressure reducing valve interposed in the last named conduit adjusted to deliver the air from the emergency tank to the carburetting tank at a lower pressure than said predetermined pressure.

3. An apparatus for producing carburetted air gas of substantially uniform calorific value comprising in combination a service air storage tank, a carburetting tank for producing carburetted gas, a gas mixer, conduits leading from the said service tank to the carburetting tank and mixer, a pipe connecting the carburetting tank and mixer, a valve interposed in the pipe from the carburetting tank to the mixer for governing

the flow therethrough, a thermostat operatively connected to the said valve, and a burner for heating the thermostat, said burner being connected to receive gas from the mixer, whereby to actuate the thermostatic valve in accordance with the calorific value of the said gas.

4. An apparatus for producing carburetted air gas of substantially uniform calorific value comprising in combination a service compressed air tank for a gaseous fluid carrier, a carburetting tank for producing carburetted gas, a gas mixer, a conduit leading from the service tank to the carburetting tank, a branch conduit leading from the first named conduit to the mixer, a pressure reducing valve interposed in said branch conduit for delivering the air to the mixer at a predetermined pressure, an emergency tank for the gaseous carrier, a pipe leading from the emergency tank and communicating with the said branch conduit intermediate the said reducing valve and mixer, a pressure reducing valve in said pipe set to initiate flow from the emergency tank and maintain a pressure in the branch conduit lower than the said predetermined pressure whenever the supply of air from the service tank fails, and a pipe connecting the carburetting tank to the mixer.

5. An apparatus for producing carburetted air gas of substantially uniform calorific value comprising in combination a service compressed air tank for a gaseous fluid carrier, a carburetting tank for producing carburetted gas, an emergency tank for air, a conduit connecting the service and carburetting tanks, a gas mixer, a branch conduit leading from the first named conduit to the mixer, a pressure reducing valve interposed in said branch conduit for delivering the air to the mixer at a predetermined pressure, a pipe leading from the emergency tank and communicating with the said branch conduit intermediate the said reducing valve and mixer, a pressure reducing valve in said pipe set to initiate flow from the emergency tank and maintain a pressure in the pipe lower than the said predetermined pressure whenever the supply of the air from the service tank fails, a pipe connecting the carburetting tank to the mixer, a thermostatically controlled valve interposed in the last named pipe, a burner connected to receive gas from the mixer for heating the thermostatic elements of the said valve whereby to actuate the valve in accordance with the calorific value of the said gas.

6. An apparatus for producing carburetted air gas of substantially uniform calorific value comprising in combination a service air tank, a carburetting tank for producing carburetted gas, a conduit for conducting air from the service tank and delivering it adjacent the bottom of the carburetting tank,

- a pressure reducing valve in the said conduit set to deliver the air at a predetermined pressure, an emergency storage tank for air, a conduit for delivering the air from the 5 emergency tank to the carburetting tank, a pressure reducing valve in the second named conduit adjusted to deliver to the carburetting tank at a lower pressure than said predetermined pressure, a gas mixer, a pipe 10 leading from the upper portion of the carburetting tank to the mixer, branch conduits leading from the said two conduits, respectively, for delivering air to the mixer, pres-
sure reducing valve in each of said branch conduits, the pressure reducing valve in the 15 branch conduit communicating with the emergency tank being adjusted to deliver at a lower pressure than is delivered by the reducing valve in the branch conduit communicating with the service tank, a valve in 20 the pipe connecting the carburetting tank and mixer, and means responsive to the calorific value of the gas produced in the mixer for actuating the last named valve.

In testimony whereof, I sign my name.
ARTHUR N. KERR
